his Attorney.

UNITED STATES PATENT OFFICE.

WILLIAM P. FRIES, OF CYNWYD, PENNSYLVANIA.

DUSTPAN.

Application filed June 13, 1925. Serial No. 36,892.

My invention relates to that type of covered dust pans which, when rocked upon the floor by the aid of a handle, automatically effects the opening of the cover and which, when lifted by the medium of the handle, automatically effects the closing of the cover and allows the case to swing and thereby cause the dust and dirt to fall into the closed end thereof.

10 Prior to my present invention numerous dust pans of the above general type have been invented, said latter mentioned dust pans being of various degrees of complexity effecting the operation of the cover by 15 means of wires, links, crank arms and flexible devices such as chains and cords.

One object of my invention is to produce an improved dust pan of the previously mentioned general type which will be of a more 20 simple construction than those previously invented.

Another object is to so make my improved dust pan that it will be durable and exceptionally neat in appearance without any objectionable exterior parts which would detract from its appearance and catch on objects during use. Owing to said simple construction and neat appearance of my improved dust pan, it is particularly desirable 25 for use by porters and attendants in the lobbies of hotels, public buildings and other places where it is necessary to clean while being closely observed.

A further object is to so arrange the parts 30 of my improved dust pan that it can be manufactured at a comparatively low cost.

These objects and other advantageous ends which will be set forth hereinafter, I attain 35 in the following manner, reference being had to the accompanying drawing in which

Figure 1 is a side elevation showing a dust pan made in accordance with my invention resting in operative position upon the floor, the cover being open,

40 Figure 2 is a side elevation of my improved dust pan showing the parts in the positions which they automatically assume when the device is lifted from the floor by the pole of the handle, the cover being closed,

45 Figure 3 is a sectional view taken on the line 3-3 of Figure 2,

Figure 4 is an enlarged fragmentary section showing the parts in the position illustrated in Figure 2,

55 Figure 5 is a perspective view of my improved dust pan in the position shown in Figure 1, and

Figure 6 is a perspective view of my dust pan illustrating the parts in the position which they assume when being carried or 60 suspended by the pole of the handle.

Referring to the drawing, 7 represents the case of the dust pan which includes a 65 closed end 8 which is preferably made of curved formation in the well known manner to allow a rocking or tilting movement of the case upon the floor as hereinafter described.

The top of the case is partially closed as shown at 9, the remaining portion being open as shown at 10, the opening also 70 extending to the end 11 so as to allow dust and dirt to be swept into the case when in the position shown in Figures 1 and 5, the front edge 12 of the bottom 13 also resting upon the floor. A cover 14 is hinged at 75

to the top of the case and when closed as shown in Figures 2, 3, 4 and 6, said cover serves to obscure the contents of the case 7. The cover 14 is preferably provided with an angular portion 16, which, when the 80 cover is closed, serves to cover that portion of the opening of the case between the front edges 17 of the opposite sides 18 and 19 of the case. Said angular portion 16 has a central hole 20 which is preferably surrounded 85 by a ring 21 by soldering or otherwise applying said ring to the portion 16. A handle 22 includes a pole 23, and a bail 24.

The pole 23 may be made of a metallic pipe with the portion 27 of the bail secured in the 90 end of the pipe preferably by notching the lower end of the pipe as shown at 28. Pivot members or trunnions 25 and 26 extend through holes 28 and 29 in the sides 18 and

19 of the case 7 and form a swinging support or pivot for the case 7, the location of said holes and trunnions being such, with respect to the center of gravity of the case 7, that when the device is lifted by the pole 23, the end 8 of the case will automatically 95 swing from the position shown in Figures 1 and 5 to the position shown in Figures 2, 3, 4 and 6. The pole 23 extends through the hole 20 and rings 21, the wall of the hole in the portion 16 and the hole of the ring,

100 when the device is completed, being in alignment so that the hole 20 may also be considered to include the hole of the ring. The 105

portion 27 and legs 30 and 31 of the bail 24 are of such dimensions that they will swing in the space between the sides 18 and 19 so that when the device is in the position illustrated in Figures 2, 3, 4 and 6, the bail will be located entirely within the case and obscured from view. The trunnions 25 and 26 are preferably joined to the leg portions 30 and 31 of the bail and screw threaded at 10 their outer ends and provided with nuts 32 and 33, the screw threading preferably being such as to prevent the nuts from binding against the sides 18 and 19. The arrangement of the parts as illustrated is such that, 15 when the cover is in its closed position, the weight of the case and the position of the lower end of the pole within the hole 20 will retain the cover in a closed position so that the cover cannot accidentally be 20 opened since the parts will be held in the position clearly illustrated in Figure 4, the diameter of the hole 20 being slightly larger than that of the pole 23. When, however, the device is lowered so that the end 8 en- 25 gages and rocks upon the floor, the pole 23 will act as a cam against the wall of the hole 20 and by maintaining a substantially vertical position of the handle during the rocking movement of the case 7, the wall of 30 the hole 20 will slide along the pole 23 and effect the opening of the cover into the position shown in Figures 1 and 5. When the pole 23 is again lifted the case 7 will swing on the trunnions 25 and 26 as a pivot with 35 the end 8 lowermost and during this action the pole 23 will again act as a cam in contact with the wall of the hole 20 and close the cover.

By following out the construction as 40 above described and as illustrated on the drawing, I have found it unnecessary to provide any complicated constructions such as present in dust pans made prior to my invention, the mere cam action between the 45 pole of the handle and the wall of the hole 20 of the cover 14 serving to both open and close the cover. Another advantage is that no exterior parts are necessary and it is unnecessary to connect the handle or any of 50 its parts directly with any part on the cover by any such means as previously set forth as being present in devices invented prior to my invention. As shown in Figure 6, the 55 case and cover are free of any attaching means with respect to the pole of the handle or adjacent parts other than the mere hinging of the cover to the case. Thus there are no objectionable projections or exterior parts which take from the neat appearance 60 of the device and the utility when the device is used for purposes above mentioned.

In the actual use of my improved dust pan as illustrated and as above described, 65 the cover has been found to freely open and close when the device is operated as above

described, the proportioning of the parts being such as to allow the use of the device in a practical manner.

Having thus described my invention what I claim as new and desire to secure by Letters Patent is:

1. A dust pan including a case; a cover; a movable connection between the case and cover said cover having a hole therethrough providing a wall, the wall of said hole being fixed relatively to the face surfaces of said cover; and a handle pivotally connected to said case off its center of gravity and having a portion extending through said hole in the cover, said hole being relatively spaced at such distance from the movable connection between the case and cover and from the pivotal connection between the handle and case as to allow said handle portion by sliding contact with one part of the wall of said hole to effect opening movement of the cover when the case is lowered, through the medium of the handle, into contact with the floor and then rocked or tilted upon the floor, said handle portion being operative by sliding contact with another part of the wall of said hole to effect closing movement of said cover when the case is lifted through the medium of said handle.

2. A dust pan including a case; a cover movably connected to said case, said cover having a hole therethrough; and a handle including a pole portion and a bail portion, the bail portion being pivotally connected to the case and adapted to swing entirely within the case, said pole portion of the handle extending out through said hole and by contact with the wall of said hole respectively effecting operation of the cover into open and closed positions when the case is rocked or tilted upon the floor and when the case is lifted through the medium of the pole.

3. A dust pan including a case; a cover movable relatively to the case and having a hole therethrough; and a handle having a portion extending downward through said hole, said portion below said hole carrying a part pivotally connecting with said case at a position above its center of gravity, said portion of the handle by sliding contact with the wall of said hole acting to operate said cover when the case is tilted relatively to said pivotally connecting part.

4. A dustpan comprising a body having a lip portion, a handle having pivotal connection internally of the dustpan with the body in such a manner that the rear portion of the dustpan will swing down when lifted from the floor by the handle, said body having a fixed hood over the rear portion thereof, and a swinging hood controlled by said handle, hinged to the front edge of the fixed hood, adapted to swing into engagement with said lip portion when the dustpan is lifted by said handle, the handle connections being

enclosed when the front hood is closed, the swinging hood being thereby automatically opened when the dustpan is placed on the floor, and automatically closed when the 5 dustpan is lifted from the floor, the handle extending through the swinging hood.

5. A structure as specified in claim 4, said hood having its front portion provided with an opening through which said handle extends, and a swinging bail within said hood and dustpan, forming said internal connection, to which said handle is attached, said

bail having pivotal engagement with the sides of the dustpan.

6. A structure as specified in claim 4, said 15 swinging hood having an opening in the front wall thereof, and said handle extending through said opening to the internal connection, having sliding endwise motion therein, thereby to open and close the hood. 20

In testimony whereof, I have signed my name to this specification.

WILLIAM P. FRIES.
